RIM PROTECTOR

James W. Trew, Gettysburg, Pa.

Application March 4, 1941, Serial No. 381,727

3 Claims. (Cl. 217—3)

This invention relates to a rim protector and has relation more particularly to a device of this kind especially designed and adapted for use in connection with a rim comprised in the structure of a lid for a fruit basket.

It is a particular object of the invention to protect the top layer of fruit or kindred basket content against rim cut when the basket lid is applied.

It is also an object of the invention to provide a device of this kind which is adapted to engage from within the rim of a basket lid and wherein the device is of such cross sectional configuration to provide effective protection for the top layer of fruit or the like within the basket against rim cut.

The novel features of my invention will hereinafter be definitely claimed.

In order that my invention may be the better understood, I will now proceed to describe the same with reference to the accompanying drawing, wherein:

Figure 1 is a view in perspective of a rim protector constructed in accordance with an embodiment of my invention unapplied and in its initially substantially straight form;

Figure 2 is an enlarged detailed sectional view illustrating the protector in applied position, the associated lid and coacting basket being illustrated in fragment.

My improved protector, as herein embodied, comprises a flexible resilient member M to engage from within the inner face of the usual depending or marginal rim 1 of a basket lid L and of a length to extend substantially entirely around the lid. While in applied position it is preferred that the free extremities of the member M be in butting relation and free of overlap. However, it is to be stated that the protector will be effective in the event overlap should occur.

The member M as herein disclosed comprises an elongated strip 2 of a material, preferably heavy paper stock, to allow for the formation and maintenance along a longitudinal margin of an outstanding flange 3 to provide a stop or shoulder to limit the extent of insertion of the member M within the lid L or inwardly of the rim 1 thereof. As herein disclosed, this flange 3 extends across the outer edge face of the rim 1.

Overlying what may be termed the outer faces of the strip 2 and the flange 3 is a lamination 4 of a material, preferably paper stock, of a weight lighter than that of the strip 2 and its flange 3. This lamination 4 has one longitudinal marginal portion adhesively connected, as at 5, to the free

5 marginal portion of the strip 2 while the second longitudinal marginal portion of the lamination 4 is adhesively secured, as at 6, to the outer longitudinal marginal portion of the flange 3. The extremities of the lamination 4 are also adhesively secured, as at 7, to the end portions of the strip 2 and flange 3.

The lamination 4 initially is of a width considerably greater than the combined widths of the strip 2 and its flange 3 so that the member M constitutes an elongated envelope or case for a filler 8 of fluffy material. While this filler 8 may be as preferred, it is particularly desired that such filler 8 constitute a pulp paper which has been effectively comminuted within a hammer mill. The pulp paper so treated results in the filler 8 consisting of a mixture of relatively fine fibres and flaky particles.

As is illustrated in the accompanying drawings, the filler 8 is relatively thick thus assuring effective protection for the top row of fruit or the like and more particularly the marginal pieces of such fruit or the like when the lid L is applied.

25 Initially the member M is substantially straight as illustrated in Figure 1 of the drawing but it can be readily flexed for application within the lid L and when so applied the inherent resiliency possessed by the member M will result in sufficient expansion to cause the member to have close contact with the inner face of the rim 1 of the lid whereby the applied member will be maintained in position during the handling of the lid L in applying the same upon the basket. 35 It is, therefore, to be particularly pointed out that the protector as herein disclosed is of a character or nature that can be readily and quickly applied without requiring any special skill.

40 I claim:

1. As a new article of manufacture, a protector for the rim of a lid for a fruit basket comprising an elongated flexible envelope, and a filler of fluffy material within the envelope, said envelope and filler providing a resilient pad to be placed within and around the lid and in close contact with the inner face of the rim of the lid, a longitudinal marginal portion of a wall of the envelope being provided therealong with an outwardly and laterally disposed flange to provide a shoulder for contact with the outer edge face of the rim.

45 2. As a new article of manufacture, a protector for the rim of a lid for a fruit basket comprising an elongated flexible and resilient pad to

be placed within the lid and in close contact with the inner face of the rim of the lid, said pad comprising two overlying and marginally connected laminations to provide a case, and a filler of fluffy material within the case, the lamination having contact with the inner face of the rim of the lid being heavier than the second lamination.

3. As a new article of manufacture, a protector for the rim of a lid for a fruit basket comprising an elongated flexible and resilient pad to

be placed within the lid and in close contact with the inner face of the rim of the lid, said pad comprising two overlying and marginally connected laminations to provide an envelope, the marginal portion of one of the laminations being outwardly and laterally disposed to provide a shoulder for contact with the outer edge face of the rim, and a filler of fluffy material within the envelope.

10

JAMES W. TREW.
